[57] CLAIM

The ornamental design for a radio control unit, as shown and described.

DESCRIPTION

FIG. 1 is a front elevational view of a radio control unit showing my new design.

FIG. 2 is a top plan view thereof;

FIG. 3 is a bottom plan view thereof;

FIG. 4 is a left side elevational view thereof;

FIG. 5 is a right side elevational view thereof; and

FIG. 6 is a top, front and right side perspective view thereof.

The broken line showing of the radio cabinet in FIGS. 2, 3, 4 and 5 is for illustrative purposes only and forms no part of the claimed design.
